UNITED STATES PATENT OFFICE.

ANDREW WICKEY, OF EAST CHICAGO, INDIANA.

BALING-PRESS.

SPECIFICATION forming part of Letters Patent No. 664,987, dated January 1, 1901.

Application filed November 11, 1899. Serial No. 736,597. (No model.)

To all whom it may concern:

Be it known that I, ANDREW WICKEY, a citizen of the United States of America, residing at East Chicago, in the county of Lake 5 and State of Indiana, have invented certain new and useful Improvements in Baling-Presses, of which the following is a specification.

My invention relates to certain improvements in baling-presses of the class in which hay, straw, or other similar material is compressed into block form.

The object of the invention is to provide in a baling-press suitable means for condensing the material to be compressed into a convenient size to be readily inserted into the baling-chamber, means for feeding said condensed material into the chamber, and means for supporting blocks such as are used between the bales in the compression thereof, together with suitable operating mechanism for driving these various parts.

To such end the invention consists in certain novel features of arrangement and construction, a description of which will appear in the following specification and the essential features more definitely pointed out in the claims.

The invention is illustrated in the drawings 30 by means of seventeen figures, of which—

Figure 1 is a side elevation of a press embodying my improvements. Fig. 2 is a detail plan view of the condensing-chamber and adjacent parts. Fig. 3 is a similar view with the upper portion of the vertical walls of the condensing-chamber cut away in the plane 33 of Fig. 1. Fig. 4 is a detail plan view of a crank-arm used in the operation of the condenser. Fig. 5 is a detail vertical section in the line 55 of Fig. 4. Fig. 6 is a vertical cross-section in line 66 of Fig. 2 looking in the direction of the arrow 6. Fig. 7 is a vertical cross-section in line 77 of Fig. 1 looking in the direction of the arrow 7. Fig. 8 is a central longitudinal section in line 88 of Figs. 2 and 7. Fig. 9 is a detail side view of certain mechanism adapted to actuate the feeding devices, the direction of the view being indicated by the arrow 9 in Fig. 16. Fig. 10 is a detail horizontal section in line 1010 in Figs. 1 and 9. Fig. 11 is a detail plan view of a block-supporting bar and dog, the parts

above the same being cut away in the plane 1111 of Fig. 1. Fig. 12 is a detail side elevation of said part with certain portions cut away in the plane 1212 of Figs. 2 and 11. Fig. 13 is a perspective view of the block-supporting bar. Fig. 14 is a detail vertical section in line 1414 of Fig. 11. Fig. 15 is a detail side elevation of the mechanism for operating the feeder, showing said mechanism in a different position to that seen in Fig. 1. Fig. 16 is an end view of the parts seen in Fig. 15 looking in the direction of the arrow 16, the frame being cut away in the plane 1616; and Fig. 17 is a detail vertical cross-section in line 1717 of Fig. 15.

Referring first to Figs. 1, 2, 3, 6, and 8, the main frame of the press will be seen to consist of a rectangular box A, supported upon wheels a a'. The compression of the material is accomplished within said box by means of a plunger b, (see Fig. 8,) operated by a pair of gears B, journaled in the forward end of the box and connected to said plunger by a pitman b', said gears receiving their movement from such gearing as is ordinarily used in presses of this class. An opening a^x is formed in the top of the box, and above this opening is a condensing-chamber consisting of a pair of horizontally-swinging side boards C C', carried by arms c c' c² c³, (see Figs. 2 and 3,) pivoted to a vertically-extending board C². The side boards C C' swing over two horizontal boards D D', supported above and upon opposite sides of the main frame of the machine by means of two longitudinally-extending bars d d', (see Fig. 6,) which also carry the vertical board C², to which the side boards are pivoted. The front portion of the condensing-chamber is closed by a wall D², the side portions of which, curved in arcs, are concentric with the pivots of the side boards. The side boards C C' are swung toward each other by means of rollers E E', (see Fig. 3,) traveling immediately above slots e e', formed in the boards D D'. The rollers E E' engage the outer edges of arms c² c³ in their movement from left to right and crowd the side boards inward. Said rollers are moved forward and backward by two rods e² e³, which are connected to the plunger b by a cross-bar e⁴. The rollers E E' are journaled upon pins e⁵, (see Fig. 5,) passing through crank-

arms e^6 , which are connected by a transversely-extending bar e^7 , upon which is secured a condenser E^2 . Between the bar e^7 and the rollers E E' are interposed blocks e^8 , which run in the slots e e' and support the rollers above the board. Upon one of the ends of each crank-arm c^6 is journaled a guide-roller e^9 , also running in the slot, and upon the opposite end of the crank-arm is pivoted one of the rods e^2 e^3 . The forward ends of the slots terminate in laterally-extending portions, the object of which is to permit of a certain amount of independent motion of the rods e^2 e^3 . When the rollers e^9 reach the ends of the slots e e' , they swing into the lateral extensions thereof, and the opposite ends of the crank-arms e^6 , to which the rods e^2 e^3 are connected, travel forward without advancing the condenser E^2 beyond the edge of the opening a^x , while the feeder forces the hay down through the opening into the baling-chamber of the press. The side boards C C' are thrown outward by the condenser E^2 striking cam-surfaces c^4 c^5 on the arms c^2 c^3 during its movement away from the opening a^x .

The feeder F (see Fig. 1) is carried by vertically-swinging arms f f' , pivoted to two standards f^2 . The arms f f' are oscillated by a pair of bars G , connected at their lower ends to reciprocating mechanism hereinafter described. The upper ends of the bars G pass through a cross-bar g , upon which is mounted a pair of brackets g' , to which the arms f are connected. Coiled springs g^2 are interposed between the brackets g' and the upper ends of the bars G , nuts g^3 being threaded upon the ends thereof to engage the springs. The lower ends of the bars G are connected to blocks H , lying in the paths of cams I I' , secured upon the gudgeons of the gears B and adapted to raise and lower said rods. One of these blocks is seen in Figs. 9, 10, 15, 16, and 17 and, as shown, is bifurcated to form two arms h h' , connected at their lower ends by a bolt h^2 . The gear-wheel B is formed with a gudgeon b^2 , journaled in a bracket b^3 , secured to the sides of the box or frame of the press, and in the ends of said gudgeon is secured the cam I by means of a bolt i , said cam rotating with the gear-wheel B and being adapted to engage the block H and raise the same. The cam I is formed with a flat bearing-surface i , adapted at certain intervals to rest against a shoulder h^3 upon the block H , and with a curved surface i^2 , preferably concentric with the axis of its rotation. The shoulder h^3 is slightly concaved, as seen at h^4 in Fig. 9, against which the curved surface i^2 of the cam I bears at certain intervals. A trigger h^5 is pivoted upon the block H at h^6 and carries upon its lower end a roller h^7 , lying in the path of the cam I' , formed upon the outer end of the cam I , said roller being engaged by the cam I' to draw the feeder down. The other end of the trigger h^5 is formed with an ear h^8 , in which is secured the rod h^9 , passing through

an ear h^b upon the block H . A nut h^a is threaded to the end of the rod h^9 , and between the nut and the ear h^b is a spring h^c , adapted to yieldingly hold the lower end of the trigger against the block, the object of which is to prevent accidental breakage to the parts in case the machine is run backward for any cause. 75

Looking at Figs. 1 and 9, the cam-surface i^2 of the cam I will be seen in engagement with the curved surface h^4 of the block H . The direction of rotation is indicated by the arrows in said figures and the plunger b is at 80 the end of its forward stroke, the feeder being held in its raised position by the cam. When the plunger is drawn almost to the end of its return stroke, the cam I' has been carried around by the rotation of the wheel B 85 and strikes the roller h^7 , drawing the feeder down and forcing the hay into the baling-chamber. The cams I I' are so arranged and timed with respect to each other that the curved surface i^2 leaves the block H the instant the cam I' strikes the roller h^7 . The cam I' draws the block down by its engagement with the roller h^7 until, when said block is at its lowest position, its surface h^3 engages the flat surface i of the cam I and is instantly 95 raised by said cam as the latter is rotated, the corner h^e of the cam riding along the horizontal surface of the block until the curved surface h^4 thereof is reached, when the feeder will be held in its raised position by said 100 curved surface i^2 until the cam leaves the block. By means of this arrangement the feeder is held at rest during a greater portion of the movement of the plunger and is brought downward to force the hay into the baling- 105 chamber and returned quickly during the end of the return stroke of the plunger. In case the gearing of the press should be run backward the cam I' will strike the roller h^7 and merely swing the trigger h^5 upon its pivot 110 without raising or lowering the feeder and without danger of breakage.

The separating-blocks are supported upon a swinging bar K , (see Figs. 11, 12, and 13,) pivoted in the frame of the machine and 115 formed with a crank-arm k , engaging a spring k' , resting upon a bracket k^2 and adapted to yieldingly hold said bar in a horizontal position. The spring k' encircles a rod k^3 , which is connected to the crank-arm k and extends 120 through an opening in the bracket k^2 . When the swinging bar K is tilted downward by a block, the rod k^3 is swung past the dead-center and the arm k engages a stop k^4 and is held there by the tension of the spring k' until the plunger b engages the bar K and returns it to its normal position. A pair of standards L are secured to opposite sides of the frame of the machine and the end D^2 of the condensing-chamber. They slightly overhang the interior of the press (see Fig. 3) and have pivoted retaining-dogs l , with rounded concave faces l' , (see Figs. 11 and 12,) adapted to be struck by the blocks, which are in- 130

serted between said standards and said end. As the block strikes the curved face l' it tilts the retaining-dog upward and may be pushed by, after which the dog falls back in place and prevents the block from slipping back. 5 A lug l^2 is formed upon the dog (see Figs. 11 and 14) and engages the plate l^3 to hold the dog in a horizontal position. The blocks are forced into the baling-chamber by means of 10 a depending arm N , pivoted to the arm f' and connected to a bell-crank lever O by a link n . Said lever is pivoted to the frame of the machine at o , and when in the position seen in Fig. 1 the arm N swings downward and to 15 the rear of the block; but when the bell-crank lever O is raised the link n is thrown forward, thus causing the arm N to swing down between the standards L , engage the block, and force the same down into the baling-chamber.

20 I claim as new and desire to secure by Letters Patent—

1. In a baling-press, a baling-chamber, a plunger reciprocated therein, a condensing-chamber opening into the baling-chamber, a 25 condenser in the condensing-chamber, crank-arms pivotally connected to said condenser between their ends, connecting-rods pivotally connected to one end of said crank-arms and to the plunger and guides for the other ends 30 of the crank-arms; substantially as described.

2. In a baling-press, a baling-chamber, a plunger reciprocated therein, a condensing-chamber opening into the baling-chamber, a condenser in said condensing-chamber, a 35 cross-bar supporting said condenser, crank-arms pivotable between their ends to said cross-bar, rods pivotally connected to one of the ends of the crank-arms and connected with the plunger, rollers upon the opposite ends of 40 the crank-arms and guides for said rollers terminating in lateral offsets, whereby, during a portion of the forward movement of the plunger, said rollers will pass into the lateral offsets and permit the opposite ends of the 45 crank-arms to move with the rods without moving the condenser; substantially as described.

3. In a baling-press, a condensing-chamber, comprising a suitable platform, end wall and 50 horizontally-swinging side walls, a condenser in said condensing-chamber, a cross-bar supporting said condenser, crank-arms pivotally connected to said cross-bar, rollers upon one of the ends of the crank-arms, guide-blocks 55 at the pivotal points of said crank-arms, longitudinally-extending slots in said platform, guiding said blocks, terminating in lateral extensions and suitable devices connected to the other ends of the crank-arms 60 adapted to draw them forward; substantially as described.

4. In a baling-press, a feeder, a bar adapted to reciprocate said feeder, a cam-block secured to the end of said bar and having a shoulder, a rotating cam having a surface 65 adapted to raise said block and a surface concentric with the axis of rotation for retaining

it in said raised position during a portion of its rotation; substantially as described.

5. In a baling-press, the combination with 70 a feeder and an actuating-bar therefor, of a rotating cam having a flat bearing-surface, a curved bearing-surface concentric with its axis of rotation, and a radially-extending cam, of a cam-block on the bar having a flat 75 bearing-surface adapted at certain intervals to be engaged by the flat bearing-surface upon the cam to raise said block and having a roller lying in the path of the radial cam and adapted to be engaged by the same, to draw the block 80 down; substantially as described.

6. In a baling-press, the combination with 85 a feeder, a cam-block connected to said feeder a rotatable cam having a bearing-surface concentric with its axis of rotation, a surface eccentric thereto, adapted to raise said block, a cam extending radially from the axis of rotation and a roller upon said block, lying in the path of said radial cam and adapted to be drawn down thereby; substantially as 90 described.

7. The combination with the feeder, of the cam-block, H connected therewith, the trigger, h^5 , pivoted upon said block and held yieldingly in one direction, a roller upon said 95 trigger, and a rotating cam adapted to engage said roller during a portion of its rotation and to draw the same downward; substantially as described.

8. The combination with the feeder, of the 100 cam-block, H connected therewith, the trigger, h^5 , pivoted thereto, a spring adapted to yieldingly hold said trigger against the cam-block, a roller, h^7 , upon said trigger and a cam adapted when rotated in one direction, 105 to engage said roller and draw the cam-block downward and to force said trigger away from the cam-block when rotated in the opposite direction; substantially as described.

9. In a baling-press, the combination with 110 a tilting bar adapted to temporarily support separating-blocks and having a crank-arm, k , of a bracket, k^2 , a rod connected to said crank-arm and passing through the bracket, a spring confined between the crank-arm and the 115 bracket and a stop, k^4 , lying in the path of the crank-arm, whereby the crank-arm will be forced against said stop, by the spring, when moved in one direction past the dead-center; substantially as described.

10. In a baling-press, the combination with 120 a frame and driving-gear, of a plunger, a pitman pivoted to the same, a gear-wheel forming a part of the driving-gear and having an eccentric connection with the pitman, a cam 125 secured to said gear and rotated thereby, a cam-block operated by the cam, a feeder, a feeder-operating arm supported upon the frame and suitable connections between the cam-block and the arm; substantially as described.

11. In a baling-press, and in combination 130 with the press and driving-gear, a division-block, a division-block holder supported on

the top of the press, a vertically-oscillating
feeder-arm, a block-inserter carried by the
feeder-arm and a device for shifting the in-
sserter with respect to the feeder-arm to cause
it to engage the block or pass by the same as
desired; substantially as described.

5 In witness whereof I have hereunto set my

hand, at Chicago, in the county of Cook and
State of Illinois, this 2d day of November,
A. D. 1899.

ANDREW WICKEY.
